UNITED STATES PATENT OFFICE

MICHAEL HAWIE, OF GREENS FARMS, CONNECTICUT

BUCKLE

Application filed June 19, 1930. Serial No. 462,235.

The present invention relates to buckles, particularly of the one-piece rustless type, adapted for use with suspenders, hose supporters, and the like, to provide for the convenient and reliable adjustment of the web of the suspender or supporter.

In buckles as heretofore constructed, having toothed or other sharp edges engaging the outer surface of the web, the latter would become cut and marked, so that it became very unsightly when through adjustment such cut and marked parts were exposed, this being especially true with soft surfaced materials.

An object of the invention is to provide a buckle which will not injure or mar the exposed surface of the web, will lie flat with respect to the web, and will be reliable in operation. Another object is to provide a buckle to which the web may be secured with great facility and which requires only one threading operation thus effecting a great saving of time in assembling. A further object is to provide a buckle requiring only a single threading of the web, and in which the slot will be of such size as to permit the use of webs of different thicknesses.

To this end I propose to make the bar disposed at the outer or exposed surface of the web without any projecting edges or flanges which would tend to raise it from the surface of the web, or to injure the outer surface of the web, and to provide the toothed or sharpened web retaining edge in such relation that it only engages the under surface of the web. I further propose to provide the exposed bar substantially in a plane with the web attaching bar to the end that the entire structure will be extremely compact, neat in appearance and without any projecting parts, either at the outer or inner surface.

With the above and other objects in view, an embodiment of the invention is shown in the accompanying drawings, and this embodiment will be hereinafter more fully described with reference thereto, and the invention will be finally pointed out in the claim.

In the drawings:—

Fig. 1 is a front elevation of a piece of web supporting a hose supporter button loop, and

showing a buckle according to the present embodiment of my invention attached thereto.

Fig. 2 is an edge view of the parts as shown in Fig. 1.

Fig. 3 is an enlarged front elevation of the buckle, before attachment to the web.

Fig. 4 is a sectional view taken along the line 4—4 of Fig. 3.

Fig. 5 is a vertical sectional view through the buckle, shown attached to the web, the latter being threaded through the buckle, as in Figs. 1 and 2.

Fig. 6 is a perspective view of the buckle, unattached, and seen from the rear.

Similar reference indicate corresponding parts throughout the several figures of the drawings.

The buckle, according to the present embodiment of the invention, is of one piece construction, preferably stamped from sheet metal, and comprises an elongated frame having a transverse web receiving slot 10, at one side of which is disposed the upper bar portion 11, while at the other side is disposed the lower bar portion 12, and at each end there are arranged rearwardly disposed flanges 13 connecting the two bar portions together and forming guides for the edges of the web when threaded and adjusted through the buckle.

At the upper edge the bar 12 is provided with an outwardly bent web gripping flange 14, preferably toothed, as shown, but which may be of any suitable formation. The bar 11 may be slightly convex as shown, to provide an ornamental appearance, or it may be otherwise suitably shaped, but preferably it lies substantially in the plane of the bar 12 and at its under side presents a relatively smooth surface to the web.

The bar 12 is provided at its lower edge with a foldable extension or lip 15 adapted to be bent upon the under surface of the bar 12 and in between the flanges 13 to secure the end 16 of the web 17 and enclose the ends of lip 15 when swedged down upon the web. The edge portion of the lip is preferably bent at a slight angle, as shown, so that it presses more firmly into the web. The bendable portion of the bar 12 and lip 15 is provided with a series of perforations 18 to re-

ceive portions of the web and to permit the lip to be more easily closed against the web, this operation being preferably performed in a suitable press. This construction not only provides a firm grip for the web, but is such that the lip will not tend to spring up after being clamped over the web.

The web, after attachment to the buckle, is carried down over the lip 15 and looped through the garter element 19, being then carried upwardly over the bar 12 and flange 14 and threaded through the slot 10, from which it extends beneath the bar 11 upwardly. Vertical pull on the web presses the inner face of the web against the bar 12 and its flange, while the outer face of the web presses against the smooth under surface and edges of the bar 11, the buckle thereby being retained in adjusted position. The buckle is very compact and lies flat and the exposed outer surface of the web is protected against injurious and unsightly abrasion. It will be observed that only one threading of the web through the slot is required, and that the slot is of such size as to readily permit different thicknesses of web to be used.

I have illustrated and described a preferred and satisfactory embodiment of my invention, but it will be obvious that changes may be made therein, within the spirit and scope thereof as defined in the appended claim.

Having thus described my invention what I claim and desire to secure by Letters Patent is:—

A one piece buckle for attachment and threading of a web, comprising a relatively narrow flat upper transverse bar portion and a wider lower bar portion separated by a slot, said lower bar portion having a forwardly disposed web gripping transverse edge and having at its other transverse edge a web attaching lip bendable toward the rear surface of said lower bar, end flanges connecting and disposed rearwardly at a right angle to said bar portions and enclosing the edges of the web attaching lip, the end of a length of web adapted to be gripped between said lower bar portion and said lip, and said web adapted to be passed through said slot beneath said upper bar.

Signed at Bridgeport in the county of Fairfield and State of Connecticut this 18th day of June A. D. 1930.

MICHAEL HAWIE.
